CLAIM

The ornamental design for a flip earring, as shown and described.

DESCRIPTION

FIG. 1 is a front view of a flip earring showing my new design with a rotatable center piece shown in a first rotational position;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a back perspective thereof;

FIG. 8 is a front perspective view thereof;

FIG. 9 is a front perspective view of the design shown in FIG. 1, wherein the rotatable center piece is in a second rotational position;

FIG. 10 is a front perspective view of the design shown in FIG. 1, wherein the rotatable center piece is in a third rotational position;

FIG. 11 is a front perspective view of the design shown in FIG. 1, wherein the rotatable center piece is in a fourth rotational position; and,

FIG. 12 is a front perspective view of the design shown in FIG. 1, wherein the rotatable center piece is in a fifth rotational position.

(Continued)

The broken lines shown illustrate portions of the flip earring and form no part of the claimed design.
